DESIGN FOR A BAND FOR A HAT

Issy Eisenberg, New York, N. Y.

Application January 16, 1937, Serial No. 67,084

Term of patent 3½ years

To all whom it may concern:

Be it known that I, Issy Eisenberg, a citizen of the United States of America, residing in city of New York, county of New York, and State of New York, have invented a new, original, and ornamental Design for a Band for a Hat, of which the following is a specification, reference being had to the accompanying drawing, forming part thereof.

The figure in the drawing is a plan view of a band for a hat showing my new design.

I claim:

The ornamental design for a band for a hat, substantially as shown.

ISSY EISENBERG.
